COAL STOKER SMOKE ELIMINATOR

Victor C. Norquist, Kansas City, Mo., assignor to
 Butler Manufacturing Company, Kansas City,
 Mo., a corporation of Missouri

Application January 7, 1933, Serial No. 650,599

1 Claim. (Cl. 110—44)

My invention relates to a coal stoker smoke eliminator and more particularly to a device for preventing "back smoking" in coal stokers. By "back smoking" I mean the escape of smoke and/or gases through the coal hopper into the space occupied by the stoker. Back smoking is occasioned by a pressure differential existing between the coal hopper and the combustion pot. It is to be remembered that the combustion pot is being fed air under slight pressure from a blower causing an increased pressure in the region of combustion. The smoking gases escape into the cellar or other place occupied by the stoker constituting a source of annoyance and a source of danger inasmuch as there is liable to be carbon monoxide present in the gases.

The prior art shows several methods of eliminating back smoking. I have found that none of the prior art devices will effectively accomplish this purpose. Those devices which take a suction on the coal hopper fail to work because the coal becomes packed around the region of the suction pipe. The suction is necessarily localized and a great deal of smoke will escape. The use of an air tight hopper is inconvenient and furthermore allows the escape of smoke and gases in a body when the hopper lid is opened for filling.

One object of my invention is to provide a device for eliminating back smoking which will preclude the packing of the suction pipe with coal.

Another object of my invention is to provide a device for preventing back smoking which may be readily installed upon existing coal stokers not provided with such devices.

Further objects of my invention will appear from the following description.

In the accompanying drawing which forms part of the instant specification and which is to be read in conjunction therewith and in which like reference numerals are used to indicate like parts in the various views;

Figure 1 illustrates an elevation partly in section of a coal stoker attached to a house heating furnace and embodying one mode of carrying out my invention.

Figure 2 is a sectional elevation of the hopper of a coal stoker fitted with my invention.

Figure 3 is a sectional view taken on the line 50 3—3 of Figure 2.

Figure 4 is a detail view showing an ejector which may be used to carry out my invention.

Figure 5 is a side elevation of a coal stoker fitted with another mode of carrying out my invention.

Figure 6 is a detail view showing a Venturi nozzle capable of being used to carry out my invention.

In general, my invention consists in forming a space free of coal which extends along one side or completely around the interior of the coal hopper. I prefer to form this space by means of a downwardly inclined baffle secured to the side wall or walls of the hopper. This downwardly inclined baffle extends toward the center 10 of the coal hopper and forms a space which for convenience I will term "a smoke box". Communicating with this smoke box is a pipe leading to an ejector device so that reduced pressure is maintained in the region of the smoke box. For 15 convenience I will term this reduced pressure "suction". The suction device will draw the smoke out of the smoke box. I may discharge the smoke so withdrawn into the furnace at any desired point or into the draft pipe from the furnace. 20 Alternatively I may discharge the smoke into the air which goes to the combustion pot.

More particularly referring now to the drawing, a furnace 1 is provided with a coal stoker which consists generally of a coal hopper 2 which 25 is set to discharge into a coal duct 3. The coal duct 3 leads to a combustion pot 4 and houses a conveyor screw 5 which is driven by an electric motor 6 through any suitable transmission gear 7. An electric motor drives a blower fan 8 30 which discharges into an air duct 9 which leads to the combustion pot and discharges air through tuyères as is well known in the art. The interior of the coal hopper 2 is provided with a downwardly inclined inwardly extending baffle 10 35 as can readily be seen by reference to Figure 3. This baffle may be fitted in any suitable manner. I prefer to attach it to one side wall of a coal hopper 2. It may extend completely around the interior of the coal hopper if desired but I have 40 found that this is not necessary in operation. The baffle 10 and the side wall of the coal hopper 2 will form a smoke box having its open end downward. Leading into this smoke box I fit the suction end 11 of an ejector 12. This ejector 45 may be in the form shown in Figure 4 or may be of the Venturi type as shown in Figure 6. I provide a branch fitting 14 to the discharge end of my blower 8. Connected to this branch fitting is a conduit 15 which leads to the ejector 12 as 50 can readily be seen by reference to Figure 1. The air passing over the ejector nozzle 16 will create a suction in the suction pipe 11 which, as pointed out above, communicates with the smoke box. The reduced pressure will draw the 55

smoke out of the smoke box discharge it through conduit 17 as shown in Fig. 1. This conduit may be led to any suitable place such as to the smoke pipe 18 or into any suitable place in the furnace.

5 If desired, the pipe may be led to discharge out doors.

Another mode of creating a suction in the smoke box and eliminating smoke is shown in Figure 5. In Figure 5, a duct 20 is secured to an air inlet 21 of the blower in the region of reduced pressure. The pipe 20 communicates to an ejector device 12 as before. Air will be drawn through air inlet 22 and will pass through pipe 20 to an ejector 12, thence to the opening of the blower 8. Smoke will be withdrawn through the smoke box as before and will pass through pipe 20 through the blower by which it is discharged through air conduit 9 to the combustion pot, whence it will pass out through the smoke pipe 18.

10 20 It is believed that the operation of my device will be clear from the foregoing description. It will be appreciated that my device will carry out the objects of my invention. The baffle 10 will prevent the coal in the coal duct from clogging up the ejector suction opening 11. Smoke passing through the coal duct 3 will pass through the

15 open end of the smoke box and will be withdrawn through the ejector, and discharged, thus preventing back smoking whether the lid of the coal stoker be open or closed.

5 It will be understood that certain features and sub-combinations are of utility and may be employed without reference to other features and sub-combinations. This is contemplated by and is within the scope of my claim. It is further obvious that various changes may be made 10 in details within the scope of my claim without departing from the spirit of my invention. It is, therefore, to be understood that my invention is not to be limited to the specific details shown and described.

15 Having thus described my invention, what I claim is:

A coal stoker including a coal hopper, a smoke collecting hood positioned within said hopper, a blower, an ejector device having an inducing 20 medium connection and an induced medium connection, means for placing said induced medium connection in communication with said hood and means for passing air from the blower through said inducing medium connection. 25

VICTOR C. NORQUIST.
